UNITED STATES PATENT OFFICE.

GUSTAVE W. MINUTH, OF CHICAGO, ILLINOIS, ASSIGNEE TO ELECTRIC ROTARY MACHINE CO., OF CHICAGO, ILLINOIS, A CORPORATION OF ILLINOIS.

FLOOR-SURFACING MACHINE.

Application filed April 28, 1927. Serial No. 187,190.

This invention relates to floor surfacing machines having a power driven surfacing drum carried by a portable frame adapted to be trundled over the floor.

5 The main objects of this invention are to provide improved means for yieldingly mounting the surfacing drum on the frame so as to permit it to automatically adjust itself to surface irregularities; to provide a 10 mounting of this kind having improved control means for varying the pressure of the drum on the surface being operated upon; to provide improved means for detachably mounting a surfacing disc in advance of the 15 drum; and to provide improved means for counteracting the mechanical vibrations of a floor surfacing machine to prevent the formation of "beats" which cause the surfacing drum to jump.

20 An illustrative embodiment of this invention is shown in the accompanying drawings, in which:—

Figure 1 is a top plan of the improved floor surfacing machine, parts being broken away and other parts being shown in section and in dotted outline.

Fig. 2 is a side elevation of the same, part of the frame being broken away for the sake of clearness.

30 Floor surfacing machines generally include a power driven rotatable abrading element carried by a portable frame which is adapted to be trundled over the floor or other surface acted upon. The abrading element is generally driven by an electric motor mounted on the frame. In floor surfacing machines heretofore in use, the vibrations of the machine have set up a "beat", causing a periodical jump of the abrading element, which resulted in the formation of 35 ridges in the surface acted upon. This objectionable beat of prior surfacing machines is eliminated in machines embodying the present invention, which include an improved form of resilient mounting for the surfacing drum which counteracts the mechanical vibrations. Improved means is also provided for supporting an abrading disc in advance of the drum.

40 In the specific form shown, the improved floor surfacing machine comprises a portable frame 1, on which is journaled an abrading drum 2 and disc 3 arranged to be driven by an electric motor 4, which is supported on top of the frame and detachably

secured thereto by bolts 5 or other suitable fastening means.

The frame or housing 1 is preferably a metal casting having a horizontal top 6, on which the motor is supported, and vertical 60 sides 7, in which is journaled a pair of front supporting wheels 8. Another supporting wheel 9 is swiveled to the rear end of the frame. Mounted at the rear of the frame and constituting substantially a part thereof, is a post 10 having a handle 11 at its upper end whereby the machine may be trundled.

Supported in the sides 7 of the frame 1, is a transversely disposed horizontal shaft 70 12, on which is pivoted a pair of levers 13 arranged at respectively opposite sides of the frame. The forward ends of the levers 13 form bearings 14 for supporting the surfacing drum 2. Projecting forwardly from the 75 bearings 14, are extensions 15 having buffer pads 16 to prevent the drum from contacting with the molding or walls of the room when the abrading disc 3 is not used.

The rear ends of the levers 13 are in the 80 form of resilient arms 17, which are connected at their outer ends to a cross bar 18. The members 13, 17 and 18 constitute virtually a resilient unitary yoke for supporting drum 2. Yielding pressure is applied to the 85 abrading drum by means of a spring 19, which acts in tension between the resilient spring 19 is connected to the cross bar 18 arms 17 and the frame. One end of the and its other end has a bolt 20 extending 90 endwise therefrom and having a wing nut 21 engaging a bracket 22 mounted on the handle post 10. The nut 21 permits an adjustment of the spring tension.

The drum 2 is adapted to be raised from 95 the floor by a push rod 23 which is connected at its lower end to the cross bar 18. The upper end of the rod 23 is pivoted to an operating handle 24 which is pivoted at 25 to the post 10. The handle 24 is adapted 100 to be clamped in position for holding the drum out of contact with the floor by a friction plate 26 mounted on the post 10 and having the usual thumb nut 27. To raise drum 2 the operator presses down on the 105 right end of handle 24.

Mounted in the frame 1, is a suction fan 28 having an inlet nozzle 29 extending to a point adjacent the periphery of the drum for removing the dust which is then drawn 110

into the fan and expelled through a pipe 30 mounted on the frame. Suspended from the outlet of the pipe 30, is a dust bag 31. The drum 2 and fan 28 are connected to the 5 motor 4 by chains or belts 32 and 33 respectively.

Mounted on the frame 1, is a supporting plate or bracket 34 which is detachably secured to the top 6 by bolts 35 or other suitable fastening means. Mounted on the forward end of the bracket 34, is a bearing 36, in which is journaled an upright spindle 37 to which the disc sander 3 is secured. The upper end of the spindle 37 engages a bell 15 crank lever 38 pivoted on a post 39 which is supported on the bracket 34. Connected to the bell crank lever is an operating rod 40 which is operated by means of a handle 41 for raising and lowering the disc 3. The 20 handle 41 is pivoted to the post 10 so as to be operable by one hand while the other hand of the operator grasps the handle bar 11. The spindle 37 is connected to the motor 4 by a chain or belt 42 and intermediate 25 gearing 43.

In operation, when it is desired to use the drum 2, the handle 24 is released so as to let the rod 23 move upward and so permit the drum to settle and adjust itself to the irregularities in the floor. The yielding connection through members 17 and 19 between the drum and frame causes a yielding pressure to be applied to the drum and the differential connection of the springs to the 35 yoke bar 18 permits the drum to tilt laterally to conform to irregularities in the surface. The vibrations of the machine are counteracted by the unitary yoke having resilient arms 17 so as to prevent the customary beats 40 from being transmitted to the drum 2.

Although but one specific embodiment of this invention has been herein shown and described, it will be understood that numerous details of the construction shown may be altered or omitted without departing from the 45 spirit of this invention as defined by the following claims.

I claim:

1. In a floor surfacing machine, including 50 a portable frame with a yieldingly supported power driven cylindrical tool thereon, the axis of which tool is disposed horizontally and is rockable vertically sufficient to accommodate said tool to floor irregularities; the 55 combination with a vertically rockable lever- age yoke the arms of which are fulcrumed medially of their length on said frame and said yoke holding the ends of said tool rotatably on its arm tips, of yielding means 60 urging the bowed end of the yoke upward to

augment the pressure of said tool on the floor, and manually operated means to force said bowed end downward against the tension of said spring to raise said tool, the said arms being resilient to accommodate limited independent up and down movement of the tool ends. 65

2. In a floor finishing machine the combination of a portable frame with a U-shaped yoke tiltably mounted thereon, a tool carried by said yoke to act on the floor, power means to operate said tool, and manual means to raise and lower said tool, said frame having fulcrums whereon said yoke is pivoted at medial points on its arms respectively, resilient means connecting the arm-joining part of said yoke to said frame and urging said arm-joining part upward, and the latter being connected to said manual means, said tool being carried by and between the free ends of the yoke arms, and the latter being resilient. 70 75 80

3. In a floor finishing machine the combination of a portable frame with a U-shaped yoke tiltably mounted on said frame, a tool carried by said yoke to act on the floor, power means to operate said tool, the latter being carried by and between the free ends of the yoke arms, said frame having fulcrums whereon said yoke is pivoted at medial 90 points on its arms respectively and adjustable manual means to rock said yoke as a whole and so raise and lower said tool, said yoke arms being resilient, to accommodate limited rocking of said tool responsive to floor unevenness, and a spring arranged adjustably to urge the tool bearing end of said yoke downward more or less strongly according to the work requirements. 95

4. In a floor finishing machine the combination of a portable frame having an up-standing post thereon for manual guiding, with a U-shaped yoke tiltably mounted on said frame, a tool carried by said yoke to act on the floor, power means to operate said tool, the latter being carried by and between the free ends of the yoke arms, said frame having fulcrums whereon said yoke is pivoted at medial points on its arms respectively and manual means to rock said 100 yoke and so raise and lower said tool, the bowed part of said yoke being connected to said manual rocking means, said yoke arms being resilient, and a spring on said post arranged to urge the tool bearing end of said 105 yoke downward. 110 115

Signed at Chicago this 25th day of April, 1927.

GUSTAVE W. MINUTH.

CERTIFICATE OF CORRECTION.

Patent No. 1,698,554.

Granted January 8, 1929, to

GUSTAVE W. MINUTH.

It is hereby certified that error appears in the printed specification of the above numbered patent requiring correction as follows: Page 1, line 88, strike out the words "spring 19 is connected to the cross bar 18" and " insert the same to follow after the words "One end of the" in line 89; and that the said Letters Patent should be read with this correction therein that the same may conform to the record of the case in the Patent Office.

Signed and sealed this 5th day of February, A. D. 1929.
